UNITED STATES PATENT OFFICE.

CHARLES B. WHITE AND FRANKLIN WHITE, OF LANDOVER, MARYLAND.

PASSENGER-CAR.

SPECIFICATION forming part of Letters Patent No. 780,847, dated January 24, 1905.

Application filed October 18, 1904. Serial No. 228,947.

To all whom it may concern:

Be it known that we, CHARLES B. WHITE and FRANKLIN WHITE, citizens of the United States, residing at Landover, in the county of 5 Prince George and State of Maryland, have invented new and useful Improvements in Passenger-Cars, of which the following is a specification.

Our invention relates to improvements more 10 especially in passenger-cars, and involves generally the seat and berth convertibility feature thereof.

As noted, our invention has for its object, among other things, to provide for the ready 15 or convenient conversion of the car into sleeping-apartments, also to effect this in a simple and inexpensive manner and so as to contribute to the comfort of the occupant and promote hygienic conditions.

20 Said invention consists of the detailed structural features substantially as hereinafter more fully disclosed, and particularly pointed out by the claims.

In the accompanying drawings, Figure 1 is 25 a longitudinal section of a passenger-car embodying our improvements, the latter being viewed in side elevation with the seat-backs shown in normal position. Fig. 2 is a like section of such car, showing the same as when 30 arranged as sleeping-apartments. Fig. 3 is a cross-section through the car intermediately of successive seats. Fig. 4 is a like section produced through a seat. Fig. 5 is a longitudinal section thereof.

35 In the carrying out of our invention we arrange in a car, as usual, the seats 1 in rows upon opposite sides of an intervening space or aisle running therethrough. Each seat in its entirety consists, preferably, of a rectangular 40 receptacle or chamber 1^x, with its closure or lid 1^x constituting the seat proper, arms 1^b, secured in the usual way to said receptacle, and a back 1^c, connected by links or bars 1^{cc} laterally to said chamber or receptacle. Said 45 receptacles or chambers, deriving their latter name from the fact that they are desired to hold the bedclothes when not in practical use and the clothes of the occupants when the latter are undressed and when not containing 50 the bedclothes, have secured to their inner

lateral surfaces ledges or strips 1^d, upon which the lids or closures 1^x rest, so as to be flush with the upper edges of said receptacles.

Each seat-back 1^c consists of a preferably upholstered member about centrally pivoted 55 to its links 1^{cc} near their upper or outer ends, said links being pivoted near their opposite ends laterally to the seat near its upper edges about centrally thereof, whereby said back itself may be axially moved or adjusted with 60 relation to said links according to the angle at which it may be desired to dispose said back to the seat and whereby said links may be moved or swung laterally and parallel with the seat and the back moved at the same time 65 in a plane above the seat from and to the relatively forward and rear edges of said seat, as in effecting the conversion of the same into a berth or bed. Each back link has each of its longitudinal edges provided with a number of 70 notches or shoulders 1^{bb} intermediately of its ends, nearer, however, to the outer or upper one. Suitably pivoted to the seat are props or dogs 2, two applied to each side of a seat. Said props or dogs are relatively arranged to the 75 links 1^{cc} of the backs and are adapted to engage the notches or shoulders 1^{bb} of said links in effecting both the propping or adjusting said links with the backs and supporting said links in horizontal position, as when the backs 80 are arranged for the conversion of the seats into berths or beds.

Curtains or portières 3 3^a are suitably suspended or hung in any practical way, preferably as shown, as by hooks and rings 3^b 3^{bb} 85 from longitudinal overhead supports 4, which may be of the car-framework, said curtains or portières being so arranged as to provide for screening off the respective berths or bed compartments one from the other and from 90 the other portion of the car.

It is noted that when it may be desired to effect the conversion of the seats into beds or berths the backs of each two contiguous or successive seats are swung bodily in the same general direction, one back being carried or disposed into a horizontal position and the other back being disposed to stand at a slight elevation or angle to the seat to form the head-rest, as is apparent. The props for the seat-back 100

moved into horizontal position are correspondingly disposed, and by the relative position of their pivots to those of the links of said back said links and props are interlocked 5 as against further downward movement, consequently effecting the retention of said back in its horizontal position. The props for the other seat-back disposed in position to form the head-rest are adjusted to engage the outer 10 or more distant notches or shoulders of the links, as indicated, for its support in position. It is also noted that the aforesaid arrangement of parts permits the ready reversibility of the seat-backs and their retention and adjustment in position when thus reversed, as 15 well as when in their initial position. Also it is observed that the pivotal connections between each seat-back and its sustaining-links allow it to automatically accommodate itself 20 to the movements of the occupant's body. It is further observed that by my arrangement of convertible seats and berths ample room is provided between the seats and overhead, which are conducive to comfort of the occupants, as well as promotive of ventilation and 25 hygienic conditions. Also it will be noted that, especially in the conversion of the seats into berths, upon the occupants retiring and arising therefrom the bedding can be readily moved to one side, or so as to permit said 30 occupants to have standing-room between the seats for convenience in dressing and robing themselves, as will be readily appreciated.

Latitude is allowed as to the details herein, 35 as they may be changed as circumstances suggest without departing from the spirit of our invention.

We claim—

1. A passenger-car, having its seats provided with reversible backs, links pivoted to 40 said backs and seats, and props or dogs pivoted to said seats, said seat-backs adapted to be adjustable to fill in the space between adjacent seats, and said props or dogs adapted 45 to engage and hold said links in either horizontal or angular position.

2. A passenger-car, having seats provided with chambers or receptacles, reversible backs, links pivoted to said backs and seats and 50 props or dogs pivoted to said seats, said seat-backs adapted to be adjusted to fill in the space between adjacent or successive seats

and said props or dogs adapted to engage and hold said links in either horizontal or angular position.

55

3. A passenger-car, having its seats, each provided with a reversible back, links connected to the seat and back and each link provided upon its relatively forward and rear edges with a number of notches or shoulders, 60 and props or dogs pivoted to the seat and adapted to engage said notches or shoulders at their free ends as when the back is in its initial or normal position, or when serving as a head-rest.

65

4. A passenger-car, having its seats each provided with a reversible back, links connected to said backs and seat and each link provided upon both its relatively forward and rear edges with a number of shoulders or notches, 70 and props or dogs pivoted to the seat and adapted to engage said notches or shoulders, said links and props or dogs having their pivots arranged to effect their interlocking action when said links, with the back, and said props or dogs are disposed in horizontal or right-lined position, as set forth.

75

5. A passenger-car, having convertible seats and berths each comprising a chambered seat or receptacle having a reversible back and 80 props or dogs pivoted to the seat to effect the retention of the back with their links in either angular or horizontal position, and curtains or portières suspended to divide up the car into compartments or berths.

85

6. A passenger-car, having convertible seats and berths, each seat having a reversible upholstered back, lateral links pivoted at their lower ends to the seat, about centrally thereof, and at their upper ends to the lateral edges of said back about centrally thereof, and having notches or shoulders upon their front and rear edges, and props, two pivoted to each side of said seat and oppositely to the front and rear edges of said links to engage 90 with said notches or shoulders, respectively.

90

In testimony whereof we affix our signatures in presence of two subscribing witnesses.

CHARLES B. WHITE.
FRANKLIN WHITE.
